RELIGIOUS CROSS STRUCTURE

Raymond F. Brennan, Attleboro, Mass.

Application April 27, 1948, Serial No. 23,489

5 Claims. (Cl. 206—19)

1

This invention relates to ornamental dual cross-structures used for ecclesiastical display purposes and consists particularly in improved means for connecting a pair of cross members either in superposed relationship or with one member erected in upright position on the other member.

One object of the invention is to provide a cross-structure comprising a base member in the shape of a Latin cross and a second similarly-shaped cross member adapted to overlie said base member in face-to-face relationship or to stand vertically on the base member.

Another object is to provide improved means for slidably connecting the two cross members in contiguous superposed relationship with the upper member forming a tightly-fitting cover for a recess or concavity in the base member which is adapted to serve as a receptacle for containing religious articles used for worship and in administering the sacraments of the church.

Another object is to provide means for connecting the upper cross member in superimposed relation to the base member with said connecting means adapted for engagement by sliding one member on the other member to a relatively short extent to render the connecting means convenient for engagement and disengagement.

Further objects of the invention are set forth in the following specification which describes a preferred form of construction of the cross members and their connecting means, with one modification thereof, as illustrated by the accompanying drawing. In the drawing:

Fig. 1 is a top plan view showing the two cross members assembled in connected relationship with one member superimposed on the other member in face-to-face arrangement;

Fig. 2 is a side view of the same showing the two cross members in connected relationship;

Fig. 3 is a side view of the base member shown with the upper member disconnected therefrom;

Fig. 4 is a side view of the upper cross member;

Fig. 5 is a top plan view of the base member showing a part of the connecting means for the upper cross member more in detail;

Fig. 6 is an end view of the base member and a rearward view of the upper cross member shown as erected in upright position on the base member;

Fig. 7 is a greatly enlarged transverse sectional view on line 7—7 of Fig. 1 showing the connecting means between the upper member and base member;

2

Fig. 8 is a perspective view of one element of said connecting means;

Fig. 9 is a fragmentary top plan view of the base member showing the lower part of the upper cross member in transverse section and illustrating one form of means for holding the upper member in upright position on the base member;

Fig. 10 is a greatly enlarged fragmentary view showing the base member and the lower part of the upper cross member which is erected in upright position thereon by means of the connecting or holding means;

Fig. 11 is a greatly enlarged transverse sectional view of the two cross members shown with the upper cross superimposed on the base member and illustrating the holding means for erecting the upper cross as disposed in an opening therein when said cross is recumbent on the base member; and

Fig. 12 is a detailed perspective view of said last-named holding means for erecting the upper cross on the base member.

Various types of composite or dual cross-structures have heretofore been designed for use by the laity and clergy for purposes of worship and in administering the sacraments of the church; for example, as a "sick-call," so-called. In these devices means are provided for attaching an upper cross in recumbent position on a base member of the same form, or for holding the upper cross in erect position on the base member, but most of these prior holding devices have not been found entirely satisfactorily in use. It is therefore one object of the present invention

to provide improved means for connecting the upper cross with the base member which is more convenient to operate and more secure for retaining the upper cross in place as a cover for the cavity in the base member used as a receptacle for religious articles. One particular object of the present invention is to provide improved connecting means that may be slidably engaged by a relatively short extent of movement of one member on the other member.

Referring to the present drawing, the base member 2 may be of the conventional shape of a Latin cross comprising a longitudinally-extending body portion 3 with arms 4 and 5 projecting laterally therefrom. The ends of the body member 3 and arms 4 and 5 of the base cross may be shaped to an ornamental contour such as with the curved points shown, or with any other artistic configuration. Preferably, the upper cross 6 is of more severe outline and formed with

square ends as shown in Figs. 1 and 6.

As illustrated more particularly in Fig. 5 the body 3 of the base member 2 is formed with a longitudinally-extending concavity 8 for storing religious articles such as a pair of candles, a receptacle for ointment, a vial for holy water and other ecclesiastical accessories. The two opposite arms 4 and 5 of the cross or base member 2 may be provided with circular recesses 9 for holding candles inserted therewith.

The upper cross 6 may conform generally to the shape of the base member 2, being usually of thinner section and adapted to mount a figure of the Christ to serve as a crucifix. The improved means for securing the upper cross 6 in closely-abutting superimposed relation to the base member 2 comprises a channel-shaped element 15, shown in perspective view in Fig. 8, which is preferably formed of metal with longitudinal runners on its sides. The connecting element 15 may be constructed by bending or folding a strip of sheet-metal into trough-shape to provide vertical sides 16 with relatively narrow flanges 17 bent outwardly at right-angles thereto. The element 15 is quite short as compared to the length of the body 3 of the base member 2, being fastened to the top of the latter at a point adjacent its cross arms 4 and 5 by means of brads 18, screws or the like such as shown in Figs. 5 and 7.

The upper cross 6 is formed on its rearward side with a relatively deep slot 29 extending longitudinally of its body portion from about midway between its ends nearly to its upper terminal. Substantially one-half of the slot 29, that is its upper half, is undercut to provide overhanging strips or shouldered ribs 24 which overhang the sides of the slot. The slot 29 with its ribs 24 form one part of the connecting means for holding the upper cross 6 in recumbent position on the base member 2, the lower straight-sided portion 22 of the slot being of a width to receive the flanged connecting member 15, whereafter the upper cross is slid longitudinally of the body 3 of the base member 2 to engage the flanges 17 with the strips or ribs 24 projecting from the sides of the upper portion of the slot. In this way the upper cross 6 may be fastened in flat superimposed position on the base member 2 by only a short sliding movement of the upper cross, thereby providing for easy and convenient connection between the cross members, see Figs. 1, 2 and 7.

As shown in Figs. 3 and 5, the base member 2 may be provided with a pin 25 adjacent the end of the holding or connecting element 15 for use in erecting the upper cross 6 in upright position at the upper end of the base member 2. The pin 25 is adapted to engage in a drilled hole 26 in the bottom of the upper cross 6 as indicated by dotted lines in Fig. 6. The pin 25 has a further function to provide a stop or detent engageable with the end of the upper portion of the slot 29 in the upper cross 6 to limit its sliding movement on the base member 2 whereby to locate the upper cross in symmetrical relation to the base member; that is, with the cross arms of the two members in substantial alinement. When assembled in this relationship the upper cross 6 provides a close-fitting cover for the cavity 8 in the base member 2 to retain the articles stored therein from being misplaced or lost.

Figs. 9 to 12 show a modified form of construction of the means for holding the upper cross 6 in erect position on the base member 2. For this purpose I provide a connecting element 28, shown

in perspective view in Fig. 12, having a head 29 with a shank 30 which may be driven into the wood or other material of the base member 2. The head 29 has its wider portion at the top and is undercut at the sides with notches 31. Preferably, the head 29 is of slightly arcuate shape in edge view or of concavo-convex form on its opposite faces, this formation of the head having certain advantages as later explained.

Referring to Fig. 11, when the upper cross 6 is superimposed on the base member 2 the head 29 of the element 28 is entered into the straight-sided portion of the slot 29 in the upper cross 6 and caused to be displaced therewith along as the upper cross is slid on the base member 2 to engage the flanges 17 of the holding element 15 with the lateral strips or ribs 24 at the sides of the upper portion of the slot. The element 28 thus has the same function as the pin 25, that is to provide a stop for limiting the sliding movement of the upper cross 6 to properly position it in symmetrical relation to the base member 2.

With this latter form of construction of the holding or attaching element 28 the upper cross 6 may be formed with a re-entrant opening or slot 32 at its lower end, see Figs. 9 and 10, the narrower side grooves 33 of which are adapted to engage with the head 29 of the element 28. It will now be seen that the arcuate or bowed shape of the head 29 provides for the frictional engagement thereof with the grooves 33 in the slot 32 to provide a firm rigid connection between the base member 2 and the upper cross 6 when the latter is erected in upright position on the base member. Through this form of construction the upper cross 6 is held firmly and prevented from turning or rotating on its axis as is the case when the pin 25 is employed, as the means for connecting the upper cross in erect position on the base member 2. In some cases the narrower portion 34 of the slot 32 may be employed for engagement with a pin 35 at the lower end of the base member 2, see Fig. 9 to reinforce the connection of the upper cross with the base member when the former is in recumbent position thereon. This engagement between the pin 35 and the narrow portion 34 thus prevents any lateral movement at the lower end of the upper cross 6 when it is in recumbent position on the base member 2.

It will be observed from the foregoing description that the present improved means for connecting the upper cross in recumbent position or in erect relation on the base member 2 provides for especial convenience in applying the two members in their different relationships. That is to say, the upper cross 6 may be placed in overlying relation to the base member 2 and slid therewith for engaging the holding means by a relatively short movement of one member with respect to the other member; and the connecting means may be as easily released to adapt the upper cross 6 to be erected in upright position on the base member 2 by engaging either the pin 25 with the hole 26 in the bottom of the upper cross, or by engaging the improved attaching element 28 with the slot 32 in the upper cross 6, whichever construction is employed.

While the invention is herein described and illustrated in two preferred forms of construction, it is to be understood that modifications may be made in the shape and arrangement of the parts of the fastening means without departing from the spirit or scope of the appended

claims. Therefore, without limiting myself in this respect, I claim:

1. A composite cross-structure comprising a base member provided with a relatively short connecting element formed with laterally-projecting flanges on its sides, said connecting element being of a length only a small fractional part of the length of the base member, and an upper cross formed with a slot extending longitudinally thereof with a straight-sided portion extending from one end and adapted to receive the connecting element therein and a continuing portion having ribs on its sides for engaging under the flanges on the connecting element when the upper cross is slid longitudinally of the base member.

2. A composite cross-structure comprising a base member of conventional form, a relatively short sheet-metal connecting element of channel-shape provided with laterally-projecting flanges extending longitudinally of its sides, and an upper cross having a longitudinally-extending slot in its rearward face wide enough in one end portion to receive the connecting element and provided with overhanging ribs extending throughout only a portion of its length in its opposite end portion and adapted to engage under the flanges on the sides of the connecting element when the upper cross is slid on the base member whereby to hold the upper member in connection therewith.

3. A composite cross-structure comprising a base member, a relatively short connecting element fastened to the top of the base member and formed with laterally-projecting flanges on its sides, an upper cross having a slot extending longitudinally thereof and shaped with a relatively wide portion at one end for receiving the flanged sides of the connecting member with projecting ribs on its sides extending throughout the remaining portion of its length and adapted to underlie the flanges on the connecting element when the upper cross is slid on the base

member, and means at the end of the connecting element engageable with the bottom of the upper cross to hold it in erect position on the base member.

5. A cross-structure comprising a base member in the form of a cross, an upper cross conforming in shape to that of the base member, means for connecting the upper cross in superimposed close-fitting relation to the base member, said upper cross formed with a re-entrant slot at its lower end, and a connecting element for holding said upper cross in erect position on the base member, said connecting element having a head of concavo-convex form in edge view to adapt it to frictionally engage the slot in the bottom of the upper cross with a binding action.

10. 4. An ecclesiastical display device comprising two members of substantially corresponding cross-shape, and means for connecting said cross members in superposed relationship comprising an element on one member having laterally-projecting flanges extending longitudinally of its sides, and a longitudinally-extending slot in the other member wide enough in one end portion 15 to receive the connecting element on the first-named member and formed with overhanging ribs extending throughout only a portion of its length adjacent its opposite end to adapt them to engage under the flanges on the sides of the connecting element when the latter is entered into the wider portion of the slot and said slotted member slid longitudinally of the other member.
